The ornamental design for a separator made in concrete for iron frames, as shown and described.

DESCRIPTION

FIG. 1 is a perspective view of a separator made in concrete for iron frames of my new design;

FIG. 2 is a left side elevational view of my new design, the right side being a mirror image thereof;

FIG. 3 is a top plan view of my new design;

FIG. 4 is a bottom plan view of my new design; and,

FIG. 5 is a front elevational view of my new design, the back elevational view being a mirror image thereof.
